UNITED STATES PATENT OFFICE.

JOHN RUPP, OF CANBY, OREGON.

DESIGN FOR A SPOON-KNIFE.

57,446.

Specification for Design.

Patented Mar. 29, 1921.

Application filed July 29, 1920. Serial No. 399,903. Term of patent 14 years.

To all whom it may concern:

Be it known that I, JOHN RUPP, a citizen of the United States, and a resident of Canby, in the county of Clackamas and State of Oregon, have invented a new, original, and ornamental Design for a Spoon-Knife, of which the following is a specification, reference being had to the accompanying drawing, forming part thereof.

Fig. 2 is a plan view.

Fig. 3 is an end view.

I claim:

The ornamental design for a spoon knife substantially as shown.

JOHN RUPP.
